FEELER-MOTION FOR LOOMS.

1,289,626.

Specification of Letters Patent. Patented Dec. 31, 1918.

Application filed March 11, 1916. Serial No. 33,645.

To all whom it may concern:

Be it known that I, PHILIPPE BOISVERT, a subject of King George V of Great Britain, and residing at Lowell, county of Middlesex, and State of Massachusetts, have invented an Improvement in Feeler-Motions for Looms, of which the following description, in connection with the accompanying drawings, is a specification, like characters 10 on the drawings representing like parts.

The invention to be hereinafter described relates to means for detecting and indicating the substantial exhaustion of the filling in the shuttle of a loom to thereupon initiate 15 filling replenishment while the loom continues to run.

Feeler mechanisms of this general type are necessarily delicate and sensitive in operation in order to prevent unnecessary actuation 20 of the replenishing mechanism when a working supply of filling is present, and on the other hand, to effect such operation when the filling has become substantially exhausted. An important feature of the 25 present invention, therefore, is to materially increase the accuracy and delicacy of operation of feeler mechanisms of that type which intermittently impinge upon means within the shuttle and perform their operation 30 through the medium of such impinging contact.

In carrying this feature of the invention into practical effect, the present invention contemplates two feeler members, one a 35 relatively fixed and one a relatively movable feeler member, which, when a working supply of filling is present on a detecting beat, enter the shuttle and feel for the filling therein and upon contact therewith by the 40 movable feeler member, both members are moved forward while still maintaining their relation unchanged; when, however, the filling has become substantially exhausted, the movable feeler member first contacting 45 with the now substantially depleted bobbin, or the few turns of filling thereon, is moved relatively to the fixed feeler member by the forward push thereon, and thereupon both feeler members engage the bobbin and are moved forward in their 50 changed relation to effect filling replenishment, as will be more fully hereinafter described.

The above and other features of the present invention will be hereinafter more fully

described in connection with the accompanying drawings which show one good practical form or embodiment of the invention.

In the drawings:

Figure 1 illustrates a top plan view of a 60 portion of a loom with the present invention applied thereto, the running shuttle being positioned for co-operation between the filling therein and the feeler device on the forward beat of the lay;

Fig. 2 illustrates a top plan view of the device, showing the relative position of parts 65 on the beatup movement of the lay when a working supply of filling is present;

Fig. 3 is a view similar to that of Fig. 2, 70 showing the relation of parts when, on the detecting beat of the lay, the filling has reached a degree of substantial exhaustion; and

Fig. 4 is a section on the line 4-4 of 75 Fig. 3.

The loom frame may be of any appropriate character to support the usual operating parts of a loom, and as shown by Fig. 1, only sufficient portion 1 thereof is 80 indicated to make clear the present invention with other features of the loom. Rotatably mounted on the loom frame is the usual change or transverse shaft 2, having the usual upright 4, Fig. 1, to which is connected the arm 3 in order to impart a rocking movement to the change or transverse shaft and effect filling replenishment under 85 conditions to be more fully described.

The position of the end portion of arm 90 3 with respect to its operating member 5 is controlled by a transmitter 6 pivoted at 7 to a suitable support substantially as indicated and fully explained in the patent to E. S. Wood and J. Northrop, No. 789,471, 95 dated May 9, 1905.

The transmitter 6 has associated therewith, a controller 8, the end 9 of which is extended into the path of movement of an actuator 10, when said actuator has been positioned due to a call for filling replenishment. In the present instance of the invention the controller 8 and actuator 10 may be substantially the same as the similar parts in the patent mentioned, the construction being such that upon forward movement of the actuator 10 when it has been positioned by a call for filling replenishment, said actuator will engage the controller 8 and by forward movement thereof, effect move- 100 105 110

ment of the transmitter to position the arm 3 for operation by its operating member 5, and thereby effect or initiate filling replenishment.

- 5 Adjustably mounted on the shipper stand or other bracket 11 connected to the loom frame is the feeler stand 12 provided with a slot 13 by which it may be adjustably secured in position as by the screws 14, Fig. 1.
- 10 Mounted in the feeler stand 12 for movement toward and from the front of the loom is the feeler slide 15, means being provided as usual and substantially as in the patent to Wood & Northrop, referred to, for yielding 15 maintaining the feeler slide 15 in its rearward position.

Pivottally mounted on the feeler slide 15 at 16, is the actuator 10, its end portion 17 being normally held in raised position by a 20 spring-pressed plunger 18, Fig. 2, substantially as in the Wood & Northrop patent hereinbefore noted. The actuator 10 is provided with a part preferably adjustable as the screw member 19, which, when the filling 25 has become substantially exhausted, is adapted to engage the front wall 20 of the shuttle on a detecting beat and thereby depress the end 17 of the actuator into operative relation with the controller 8, and upon 30 frontward movement of the feeler slide to move the controller 8 and through the transmitter initiate filling replenishment.

The parts so far described may be all of the general character of the similar parts 35 disclosed in Wood & Northrop patent, or otherwise, as desired.

The feeler member 15 has at its rear portion, a web 21 which, for identification, will hereinafter be termed the feeler guide, because 40 of the fact that it guides the movement of the movable feeler member as will presently be explained. Secured to the feeler guide 21 in fixed position, is the feeler member 22 which, for identification, will be 45 known as the fixed feeler member. The feeler member 22 has a filling-engaging end portion 23 which extends substantially parallel to the longitudinal axis of the shuttle or filling carrier therein, substantially as indicated in Fig. 2.

Pivottally mounted at 24 on the feeler guide, is the movable feeler member 25, having the engaging portion 26 which, when the movable feeler member is in normal or feeling 55 position, is inclined to the longitudinal axis of the shuttle or filling carrier therein. The engaging end 26 of the movable feeler member is provided with a series of teeth or a roughened portion 27 which extends 60 rearward of the longitudinal engaging edge 23 of the fixed feeler member, the construction being such that upon a detecting beat-up movement of the lay when a working supply of filling is present, the teeth or roughened portion 27 of the movable feeler mem-

ber 25 will engage and sink into the filling mass and be by such filling held from movement relative to the fixed feeler member 23 and upon further frontward movement of the lay, the feeler, together with the feeler 70 member 22 will be moved by the frontward push of the filling mass against the movable feeler member 25.

Under the conditions just described, it will be noted that the feeler member 25 contacts 75 with the filling mass on the detecting beat and that the engaging end of the feeler member 22 is some distance frontward of the filling mass in the shuttle. When the parts are in this relation, the portion 19 of 80 the actuator is prevented from contacting with the shuttle wall 20 on the detecting beat, and this condition will be continued until the working supply of filling has become practically exhausted. When the filling has reached the desired degree of exhaustion to call for replenishment, the toothed edge portion 27 of the movable feeler member 25 will no longer be held from movement longitudinally of the shuttle by the 90 filling mass therein, but will be permitted to be moved in said direction by the frontward push of the filling carrier or bobbin, substantially as indicated in Fig. 3, whereupon the part 19 of the actuator 10 will engage the front wall 20 of the shuttle and on the continued frontward movement of the lay, the end 17 of the actuator will be depressed and then the actuator and feeler members be moved frontward as the lay continues its beat-up movement, thereby initiating filling replenishment as hereinbefore described.

It will be noted that when the fixed and movable feeler members 22 and 25 respectively are in their normal or feeling positions as indicated in Fig. 2, the edge portion 23 of the fixed feeler member does not engage the filling mass because the toothed portion of the movable feeler member 25 extends rearwardly beyond the engaging face of the member 22. When, however, the filling has become substantially exhausted, and the movable feeler member has been moved longitudinally of the shuttle by the 110 forward push of the bobbin as described, its inclined edge portion 26 will be brought into substantial parallelism with or into alignment with the edge portion 23 of the fixed feeler member, and thereupon both feeler members will be engaged by the filling carrier or bobbin, or the small amount of filling still remaining thereon, and frontward movement of the filling slide will be effected thereby after the actuator has been moved 115 120 In the present form of the invention, the movable feeler member 25 is pivotally mounted to swing in a plane extending longitudinally

nally of the shuttle, and means are provided for normally holding the movable feeler member 25 in feeling position. In the present instance, the said means consists 5 of a spring 28. This spring 28 is preferably inclosed to prevent accumulation of lint thereon, and in the present instance, this is effected by making an opening in the fixed feeler member 22 and a similar transverse 10 opening in the movable member 25, the end portions of the spring as at 29 being turned over outside these openings on the respective feeler members, or secured thereto in any appropriate manner, the construction 15 being such that the spring 28 normally tends to hold the movable feeler member 25 in feeling position with its edge portion 30 in contact with the adjacent edge portion 31 of the fixed feeler member 22 which 20 thereby acts as a stop to determine the position of the movable feeler member 25.

In order that the pivotal movement of the movable feeler member 25 shall be confined to a direction extending longitudinally of 25 the shuttle, said feeler member is provided with a slot 32, Fig. 4, between its top and bottom walls, as indicated in said figure, into which extends the feeler guide 21, the construction being such that when the movable feeler member 25 is moved about its pivotal mounting 24, the feeler guide 21 acting in the slot 32, will confine movement of the movable member 25 to a plane extending longitudinally of the shuttle axis.

35 From the construction hereinbefore described as a good practical form of the present invention, it will be noted that when the filling has become substantially exhausted and the movable feeler member has been 40 moved in a direction longitudinally of the shuttle to permit the actuator to engage the shuttle body and become operatively positioned thereby with respect to the controller, the fixed feeler member 22 engages the bobbin or the small amount of filling still remaining thereon and by forward movement 45 of the feeler slide, thereby taking the strain of such movement from the actuator and the movable member of the feeler.

It has not been herein regarded as necessary to describe the lay 33, the shuttle-box 34, the shuttle 35, nor to show the opening in the front wall of the shuttle-box 34 in the 55 shuttle 35, because these parts are well known and may be of usual construction.

What is claimed is:

1. In a feeler motion for looms, the combination of a feeler slide, an actuator for 60 effecting filling replenishment and adapted to engage a part carried on the lay, a feeler member movable longitudinally of the shuttle for controlling the engagement of the actuator with the said part and held from end movement by the mass of filling when a

working supply is present to prevent engagement of the said part with the actuator and movable longitudinally of the shuttle by forward push of the bobbin when the filling becomes substantially exhausted to 70 permit engagement of the said part with the actuator.

2. In a feeler motion for looms, the combination of a feeler slide, a controller, an actuator normally held in inoperative relation to the controller and movable at times to operative position by engagement with the shuttle or shuttle-box, a feeler member having an offset pivotal connection with the feeler slide, means for holding the feeler 80 member normally in feeling position, said feeler member having a toothed portion for engagement with the filling in the shuttle to be held from movement longitudinally of the shuttle when a working supply of filling 85 is present to prevent operation of the actuator by the shuttle and movable longitudinally of the shuttle when the supply of filling becomes substantially exhausted to permit the shuttle to operate the actuator. 90

3. In a feeler motion for looms, the combination of a feeler slide, an actuator for effecting operations in the loom mechanism through engagement with a part carried by the lay on a detecting beat, a feeler member 95 for controlling the engagement of the actuator with the said part, the said feeler member being held from movement longitudinally of the shuttle by the filling when a working supply is present and being movable longitudinally of the shuttle by the forward push of the bobbin when the filling is substantially exhausted to permit engagement of the said part with the actuator, yielding means to hold said feeler member 100 from said longitudinal movement and in feeling position when the feeler member is not engaged with the filling in the shuttle, a relatively fixed feeler member having a portion to act as a stop to the movement of 105 the movable feeler member under the impulse of said yielding means. 110

4. In a feeler motion for looms, the combination of a feeler slide, an actuator mounted on the slide and movable to operative position to effect filling replenishment by engagement with the shuttle, a feeler member having the plane of its face which contacts with the filling at an angle with the longitudinal axis of the shuttle and held from movement longitudinally of the shuttle by the mass of filling when a working supply is present, the said member being movable longitudinally of the shuttle by the forward push of the bobbin when the filling 125 is substantially exhausted and assuming a position to bring the plane of its contacting face substantially parallel with the axis of the shuttle to permit the shuttle to move the actuator into operative position, and a feeler 130

guide connected to the feeler slide and engaging the said movable feeler member.

5. In a feeler motion for looms, the combination of a feeler slide, an actuator mounted on said slide to effect operation in the loom mechanism through engagement with the shuttle, a fixed feeler part carried by the feeler slide, an adjacent feeler part pivotally mounted on the slide and projecting beyond the end of the fixed part to engage and be held from movement longitudinally of the shuttle by the filling until substantial exhaustion thereof and to then be moved in said direction by the 10 forward push of the bobbin as the lay beats up to permit the fixed part to enter further into the shuttle and the actuator to engage and be operated by the shuttle, said pivotally mounted feeler part having a slot, 15 and a feeler guide engaging said slot to guide the pivotal movement of said feeler part.

6. In a feeler motion for looms, the combination of a feeler slide, an actuator carried by the slide and adapted to be positioned by the forward push of the shuttle to effect filling replenishment, a fixed feeler member and a pivotal feeler member carried by the feeler slide, a spring extending between said two feeler members and normally acting to hold the pivoted feeler member in feeling position for engagement with the filling or bobbin before the actuator can engage the shuttle and permitting the feeler member to be moved on its pivot in a direction longitudinally of the shuttle by the forward push of the bobbin when the filling is substantially exhausted to enable the actuator to engage the shuttle body and initiate filling replenishment, and a stop carried by the fixed feeler member for limiting the movement of the pivoted feeler member.

7. In a feeler motion for looms, the combination of a feeler slide having a fixed feeler member, a pivoted feeler member having its filling engaging end extending beyond the end of the fixed member in feeling position, a spring extending between said two members and normally acting to hold the pivoted feeler member in feeling position that its end may be engaged and held from movement longitudinally of the shuttle until the filling reaches substantial exhaustion, and an actuator adapted to be engaged by the shuttle to effect filling replenishment when the filling is substantially exhausted and the pivoted feeler member is turned upon its pivot in a direction longitudinally of the shuttle by the forward push of the bobbin to bring its engaging end into alignment with the fixed feeler member.

8. In a feeler motion for looms, the combination of a feeler slide, an actuator carried by the slide and adapted to be moved by engagement with the shuttle on a detect-

ing beat, two feeler members mounted on the feeler slide, one a relatively fixed feeler member having an engaging end substantially parallel to the longitudinal axis of the shuttle, and the other a relatively movable feeler member having an engaging end inclined to the longitudinal axis of the shuttle when said member is in normal feeling position, and provided with a toothed portion extending rearward of the edge of the relatively fixed feeler member to engage the filling and hold the movable feeler member from movement relative to the fixed member when a working supply of filling is present and effecting relative movement of said movable member to bring the engaging end thereof into substantial parallelism with the edge of the relatively fixed member when the filling is substantially exhausted, and permit operation of the actuator by engagement with the shuttle.

9. In a feeler motion for looms, the combination of a fixed feeler member, a second feeler member having an inclined end portion movable relatively to the fixed feeler member in a direction longitudinally of the shuttle and held from such longitudinal movement by the mass of filling in the shuttle when a working supply is present and movable longitudinally of the shuttle by the forward push of the bobbin when the filling is substantially exhausted, and means for initiating filling replenishment when on a detecting beat the second member is moved longitudinally of the shuttle.

10. In a feeler motion for looms, the combination of a relatively fixed feeler member, a relatively movable feeler member provided with a filling engaging portion projecting beyond the fixed feeler member, a spring connecting the feeler members, said movable feeler member being movable in a direction longitudinally of the shuttle by the forward push thereon and held from such movement by the filling until it is substantially exhausted, and means for initiating filling replenishment.

11. In a feeler motion for looms, the combination of a relatively fixed feeler member and a relatively movable feeler member having a filling engaging portion projecting beyond the end of the relatively fixed feeler member, a spring normally acting to maintain the feeler members in their normal relation and permitting the relatively movable feeler member to be moved longitudinally of the shuttle when the filling is substantially exhausted on a detecting beat, and means moved by contact with a part on the lay to initiate replenishment of filling when the movable feeler member is moved longitudinally of the shuttle on a detecting beat.

12. In a feeler motion for looms, the combination of a relatively fixed feeler member, a relatively movable feeler member provided

with a toothed portion extending rearwardly beyond the end of the relatively fixed feeler member and held from movement longitudinally of the shuttle by engagement with the filling until substantial exhaustion thereof and then displaced longitudinally of the shuttle by the forward pressure upon it to permit the relatively fixed feeler member to enter farther into the shuttle, and means 10 for initiating filling replenishment when on a detecting beat the relatively movable toothed feeler member is moved longitudinally and permits the farther entrance of the relatively fixed feeler member into the 15 shuttle.

13. A feeler motion for looms, comprising, in combination, two feeler members to enter the shuttle one of which is movable in a direction longitudinally of the shuttle relatively to the other by the forward pressure of the filling carrier when on a detecting beat the filling in the shuttle has become substantially exhausted, means for normally maintaining both of said feeler members 20 yieldingly in rearward position, and means actuated by a part carried by the lay when said movable member is moved longitudi- 25

nally by the forward pressure owing to the substantial exhaustion of filling to initiate filling replenishment. 30

14. In a feeler motion for looms, the combination of a relatively fixed feeler member, an actuator having a predetermined relation to the fixed feeler member and adapted to be operatively positioned by a part carried by the lay when the fixed feeler member enters the shuttle an abnormal amount, a relatively movable feeler member having a toothed portion extending rearwardly beyond the end of the relatively fixed feeler 35 member and held from movement longitudinally of the shuttle by engagement with the filling until substantial exhaustion thereof and then displaced longitudinally of the shuttle by the forward pressure to permit 40 the relatively fixed feeler member to enter the shuttle an abnormal amount to effect operative positioning of the actuator. 45

In testimony whereof, I have signed my name to this specification.
